UNITED STATES PATENT OFFICE.

SEWARD N. MIGHELL, OF CHICAGO, ILLINOIS.

COAL-MINING MACHINE.

No. 827,746.

Specification of Letters Patent.

Patented Aug. 7, 1906.

Application filed September 26, 1905. Serial No. 280,170.

To all whom it may concern:

Be it known that I, SEWARD N. MIGHELL, a citizen of the United States, residing at Chicago, in the county of Cook and State of Illinois, have invented certain new and useful Improvements in Coal-Mining Machines, of which the following is a specification.

The principal object of this invention is to provide a simple, economical, and efficient coal-cutting machine for use in connection with coal-mining.

Other objects of the invention will appear from an examination of the drawings and the following description and claims.

It consists, further and finally, in the features, combinations, and details of construction hereinafter described and claimed.

In the accompanying drawings, Figure 1 is a plan view of a portion of a cutting-frame and cutter-head provided with my improvements; Fig. 2, a similar view of the parts shown in Fig. 1, with the top plate of the cutter-head removed and showing the roller-guiding slot or race and the manner of mounting the rollers in operative engagement with the chain; Fig. 3, a detail plan view of the roller-retainer; Fig. 4, an enlarged cross-sectional elevation of the cutter-chain and cutter-head, showing the roller-retainer; and Fig. 5, a plan view of the "long-wall" type of mining-machine provided with my improvements.

In the art to which this invention relates it is very desirable to provide a cutter-head or cutting-frame with suitable means for reducing the friction of the cutter-bit-carrying chain mechanism. It is also very desirable to provide simple and efficient means for minimizing the side and end thrust upon the cutting-frame and by reducing such friction and side thrust to enable a frame of the minimum weight and thickness to be used, whereby a narrow cut will provide a sufficient clearance both above and below the cutting-frame to permit its successful operation.

In order to accomplish these objects and other objects which will be readily apparent to those skilled in the art, I provide a cutting-frame formed of side members *a*, having a cutter-head *b*, provided with a top plate *c* and a roller-retainer *d* and a bottom plate *l*. Mounted in this frame is the cutter-chain or cutter-bit-carrying chain formed of bit-car-

rying sockets or chucks *e*, flexibly connected together by means of links *f* and pivot-pins *g*. Each of these socket members of the chain is provided with an opening *h* for receiving a cutter-bit. Upwardly and downwardly extending guiding-lugs *i* and *j*, preferably integral with the socket or chuck members of the chain extend into sliding engagement with the retaining-shoulder portions *k* of the lower plate *l* of the cutter-head and with the retaining-shoulder portions *m* of the top plate of the cutter-head, respectively.

The roller-retainer *d* is provided with an endless tortuous slot or race *n* in both its upper and lower sides. These slots extend in endless loop form, one lap being adjacent to the portion of the cutter-chain which supports the cutting-bits in cutting engagement with the coal and the other lap extending across from one lap of the chain to the other between the driving-sprocket and the portion of the chain which supports the operating or coal-engaging cutter-bits. A series of movable antifriction-rollers *o* are mounted independently of the cutter supporting or carrying chain in such upper and lower slots, respectively, of the roller-retainer, the upper rollers being provided with guiding-trunnions *p*, which are mounted in the guiding slot or race in the upper side of the retainer, and the lower series of rollers being provided with similar trunnions *q*, which are mounted in the lower socket portion of the retainer. The rollers on both sides of the retainer are thus all movable into engagement with the cutter-carrying chain and adapted to be driven thereby. They are also all movable out of engagement with the chain and are guided entirely independently of the chain by the roller-retainer from the point where they cease to actively engage the chain back to the point where their operative engagement with the chain begins.

The socket members and connecting-links of the chain are all flat at the back sides thereof, so that the back of the entire chain is substantially flat or uniform throughout, except where it is uniformly curved around the corners of the cutting-frame. The back of the chain engages the antifriction-rollers, so as to move therewith, while the cutting-bits supported by the roller-engaging portion are in cutting engagement with the coal to be oper-

ated upon. In other words, the substantially flat-backed chain is backed up or supported by the rollers throughout that portion which carries the cutting-bits while in active cutting engagement with the coal, and sprocket wheels or pulleys for this purpose are dispensed with, also the relatively thick and heavy cutting-frame and wide cut which the use of such wheels implies. The inner 5 lap of the roller-guiding slot is adapted to guide the rollers back to initial position entirely independently of the cutting-chain. This arrangement of the antifriction-roller mechanism enables the chain-driving mechanism to be mounted in operative engagement with the chain between the rollers and chain in the type of cutting-frame shown in Figs. 1 and 2 and also in the type of machine shown in Fig. 5.

20 By the above arrangement the rollers are so supported back of the cutting portion of the chain as to reduce the friction accompanying the operation of the chain to a minimum and also minimize the side thrust due 25 to the friction which must be overcome by additional power in machines of ordinary construction. It will also be noted that the series of antifriction-rollers in the return portion of the guiding-slot are guided from the 30 position where the chain leaves cutting engagement with the coal back to the position where the cutting engagement begins, so as to provide a space r , as shown in Fig. 5, between such return series of rollers and the 35 driving sprocket-wheel s not only in the type of machine shown in Fig. 5, but also in the type of machine or cutting-frame illustrated in Figs. 1 and 2. In Fig. 5 the cutting-frame is of that type which is adapted to 40 cut on opposite sides of the machine, as circumstances may require, the cutter being provided with cutter-bits t , adapted to be reversed as the position of the cutting-frame is reversed from one side of the machine to the 45 other. In Fig. 5 the lap of the cutting-chain at the right of the cutting-frame is in position to perform the cutting operation, the cutting-frame being mounted in a suitable carriage u , having supporting-wheels v , mounted upon 50 tracks w . The antifriction-rollers shown in this figure are identical with those shown in Figs. 2 and 4, the roller-retainer being modified only in form or proportions to conform to the type of machine in connection with which 55 it is shown. The rollers at the right-hand side of the cutting-frame therefore engage the cutting-lap of the chain when the machine is in use with the cutting-frame on the side of the machine shown in said figure.

60 It will be readily understood that when the position of the cutting-frame is reversed and the cutting-bits reversed the idle lap of the chain, as shown in Fig. 5, will become the cut-

ting portion thereof, and the rollers behind such lap will become the active members of 65 the roller mechanism, those on the opposite side becoming the idlers. In any case the rollers thus provided extend in supporting engagement with the chain throughout the entire length of the cutting portion thereof, 70 and they extend away from the chain as soon as the portion engaged by the rollers reaches a position where the cutting-bits supported thereby are no longer in cutting position.

I claim—

1. In a machine of the class described, the combination of a supporting-frame portion, a cutter-head, a cutter-chain movably mounted thereon, said cutter-head being provided with a single endless tortuous raceway having one lap adjacent the portion of the cutter-chain which supports the cutting-bits in cutting engagement with the material operated on, and a series of movable antifriction-rollers in the raceway mounted adjacent to and 80 in contact with the cutter-chain, said rollers being independent of the chain and of each other and forming a backing for the cutter-chain throughout the effective or cutting length of the chain.

2. In a machine of the class described, the combination of a frame, a cutter-chain provided with socket portions having openings for receiving cutting-bits, a series of movable antifriction-rollers mounted adjacent to the 95 chain and in contact therewith throughout its entire effective or cutting length, said rollers being independent of the chain and of each other and a roller-retainer mounted in such frame provided with an endless roller-guiding slot in which said antifriction-rollers are mounted.

3. In a machine of the class described, the combination of a frame, a cutter-chain provided with socket portions having openings 105 for receiving cutting-bits, a series of movable antifriction-rollers mounted adjacent to the chain and in contact therewith throughout its entire effective or cutting length, said rollers being independent of the chain and of each other and a roller-retainer mounted in such frame provided with an endless roller-guiding slot in which the antifriction-rollers are mounted, the slot and a portion of the rollers mounted therein extending away from 110 the chain throughout a portion of its length forming a space for receiving a chain-driving mechanism.

4. In a machine of the class described, the combination of a frame, a cutter-tool-supporting chain provided with projecting socket portions, a series of antifriction-rollers 120 movably mounted in contact with the inner side of the tool-supporting chain opposite the projecting socket portions thereof, said rollers being independent of the chain and of 125

each other and in contact with the chain throughout its entire effective or cutting portion, and a roller-retainer mounted in such frame provided with endless roller-guiding slots on the upper and lower sides thereof adapted to hold the antifriction-rollers in contact with the portion of the chain which supports the tools in cutting engagement with the coal to be operated upon.

SEWARD N. MIGHELL.
